WIRE STITCHING MACHINE

Joseph N. Pagliarul, Milwaukee, Wis.

Application January 11, 1938, Serial No. 184,445

3 Claims.

(Cl. 1—15)

This invention relates to improvements in wire stitching machines.

In my prior Patent No. 1,522,974, dated January 13, 1925, there is disclosed a wire stitching machine including a horizontally disposed U-shaped member, one arm of which forms a support for the box blank, and the other arm of which supports the stitching mechanism. This type of structure operates satisfactorily on box blanks of normal size. If, however, the blanks are unusually long, considering the distance from the top flap to the bottom flap, then there is interference from the closed end of the U-shaped supporting arm shown in said prior patent, because said closed end prevents the blanks from projecting there beyond while maintaining the overlap in proper condition for stitching.

It is one of the objects of the present invention, therefore, to provide a stitching machine of the same general type as that shown in my prior patent above mentioned and including a box blank supporting bar and an L-shaped stitching mechanism support carrying said bar in a manner so that the point of connection between the L-shaped member and the bar is so constructed as to accommodate a projecting portion of an unusually long box to permit the latter to project beyond said point of connection while a portion remote therefrom is being operated upon by the stitching mechanism.

A more specific object of the invention is to provide a structure as above described wherein the L-shaped member adjacent one end of which the stitching mechanism is supported, has one arm provided with a channel on its lower end, which channel is laterally offset from the arm, and wherein the channel is so associated with the blank supporting bar as to provide a groove within the channel above said bar, the said groove being adapted to accommodate one projecting edge of the box blank and the other projecting edge being adapted to pass over the offset top portion of the channel.

A further object of the invention is to provide a structure as above described including a stop gauge for the projecting portion of a long blank, and means for adjustably supporting said stop gauge beyond the point of connection between the L-shaped bracket member and the box-supporting bar.

With the above and other objects in view, the invention consists of the improved wire stitching machine and all its parts and combinations as set forth in the claims and all equivalents thereof.

In the accompanying drawings illustrating one

complete embodiment of the preferred form of the invention in which the same reference numerals designate the same parts in all of the views:

Fig. 1 is a perspective view of the wire stitching machine illustrating a gravity conveyor for box blanks to be stitched and illustrating a box blank being operated upon;

Fig. 2 is a side elevational view of the stitching device;

Fig. 3 is an enlarged sectional view taken on line 3—3 of Fig. 2 showing a box of major length in position on the device;

Fig. 4 is a view of one side of the structure illustrated in Fig. 3; and

Fig. 5 is a side view of the extension bar.

The numeral 1 designates a standard which has at its upper end an outstanding horizontal arm. Stitching mechanism is carried by the outer end of said arm. An L-shaped bracket 20 member extends from the aforementioned horizontal arm. The stitching mechanism may include a reel 14 of stitcher wire, from which the wire is led through a guide 16, through rollers 15 to a cutter 17, the cut section of wire being operated upon in a well-known manner by a staple forming member 18 and driver 19 to drive the staple through overlapping portions of a box blank and clinch the same in staple form. Any suitable form of stitching or securing mechanism 30 may be utilized.

The other arm of the L-shaped member 2 projects downwardly and has its lower end formed with a channel 9, which channel is laterally offset from the arm as clearly shown in Fig. 3 to 35 permit an edge portion of the box blank to pass thereover, as will be hereinafter described in greater detail. The channel 9 has a side opening, and within said channel a bar 3 is supported. Bolts 6 extend through apertures in the closed side of the channel and are threaded into the bar as clearly shown in Fig. 3 to support the same against the bottom of the channel. The channel is of such height with respect to the width of the bar 3 as to leave a space or groove 45 10 above the bar 3 as clearly indicated in Fig. 3. The apertures in the channel 9 through which the bolts 6 extend may provide sufficient clearance so that a slight adjustment in the position of the bar 3 within the channel may be effected 50 by manipulation of the set screw 7. This will in effect vary to some extent the vertical height of the groove 10.

An extension bar 12 may have a threaded end portion 11 for insertion in the end of the main 55

bar 3 as shown in Figs. 2 and 4, to thereby increase the effective length of said bar 3. The extension bar 12 may carry an adjustable stop gauge 21 which is cooperable with a projecting end of the box blank.

In use the box blanks to be stitched may be placed on a suitable conveyor such as the conveyor 11, and the operators may remove the blanks one at a time from the stack nearest to the stitching machine. The boxes are folded around the bar 3 with the stitching lap overlapped by the opposite edge of the box, and said overlapped portions supported on the upper surface of the bar 3. For boxes such as those shown in Fig. 1 which are of no greater length, in a direction longitudinally of the bar 3, than the length of the L-shaped member 2, there is no particular problem. However, when boxes are being stitched which are of greater length than the length of the L-shaped member 2, then when the first stitches are being inserted, there will be portions of the blank remote therefrom which must be suitably accommodated to avoid interference from the point of connection between the L-shaped member 2 and the bar 3.

Accordingly such projecting portions of a relatively long blank are accommodated in the manner shown in Fig. 3, the overlapped stitching flap being accommodated by the groove 10, and the overlapping edge being adapted to pass over the laterally offset top portion of the channel 9 in the manner shown in Fig. 3. Such projecting portions of the blank may extend beyond the channel, and the stop gauge 21 may then be suitably adjusted to cooperate with said projecting portions of the blank so that the part of the blank being stitched will be in proper position with respect to the stitching mechanism. This is important because railroad specifications require that the staples be not farther away than a predetermined distance from the flap creases. After the first set of staples are inserted, the box blank is moved toward the left, referring to Fig. 1, and subsequent staples are inserted, the gauge at the left end of the bar in Fig. 1 being employed in the usual manner to properly position the last staple. After this last staple is inserted, the stitched blank is slid off of the open end of the bar 3 and may be placed on the table 20.

From the above it may readily be seen that a construction is provided for operating upon box blanks of any desired length, without reference to the length of the L-shaped member 2. It may further be seen that this is accomplished through a particular type of connection between the L-shaped member 2 and the bar 3, which connection provides a groove within which one of the edge portions of the blank may be accommodated, and also provides an offset over which the other edge portion of the box blank may extend. Thus the box blank may project beyond the channel 9, and the overlapped portions beneath the stitcher will in no way be interfered with, nor urged out of proper alinement. It is to be understood that the invention is applicable to structures including other mechanisms for securing the overlapped portions together, such as gluing or taping mechanisms.

Although only one form of the invention has been shown and described, it is apparent that various changes and modifications may be made,

and all of such changes are contemplated as may come within the scope of the claims.

What I claim is:

1. In a machine for securing the overlapped edge portions of a set-up box blank together, an elongated bar on which said overlapped portions are adapted to be supported in a position extending longitudinally of said bar whereby the box is suspended from the bar and is supported solely thereby, a substantially L-shaped member having one arm connected to said bar, means associated with the other arm of the L-shaped member for securing the overlapped portions of said box blank together, there being means at the point of connection between the first arm of the L-shaped member and the bar for accommodating a portion of a relatively long box blank to permit the latter to project beyond said point of connection while a portion remote therefrom is being operated upon by the securing mechanism, a stop gauge for said projecting portion of the blank, and removable means for adjustably supporting said stop gauge beyond the point of connection between the first leg of the L-shaped member and said bar.

2. In a machine for securing the overlapped edge portions of a box set-up blank together, an elongated bar on which said overlapped portions are adapted to be supported in a position extending longitudinally of said bar whereby the box is suspended from the bar and is supported solely thereby, a substantially L-shaped member having one arm connected to said bar, means associated with the other arm of the L-shaped member for securing the overlapped portions of said box blank together, the connection between the first arm of the L-shaped member and the bar including a channel open at one side through which the bar extends, means for securing the bar in a lower portion of the channel to leave a groove there above for accommodating a portion of a relatively long box blank to permit the latter to project beyond said channel without interference therefrom, and means for adjusting the position of the bar in the channel to vary the depth of said groove.

3. In a machine for securing overlapped edge portions of a set-up box blank together, an elongated bar on which said overlapped portions are adapted to be supported in a position extending longitudinally of said bar whereby the box is suspended from the bar and is supported solely thereby, a substantially L-shaped member having one arm provided with a channel on its lower end which is offset laterally from said lower end, means for securing said bar within said channel, said bar being of such cross-sectional size as to leave a groove there above within the channel for accommodating one edge portion of a relatively long box blank to permit the latter to project beyond said channel without interference therefrom, the other edge portion of the box blank being adapted to project over the top of the offset channel, said L-shaped member having its other arm positioned above the bar and extending longitudinally thereof, and mechanism associated with said arm for securing overlapped portions of the box blank together at a point removed from the channel.

JOSEPH N. PAGLIARUL.
